UNITED STATES PATENT OFFICE.

ALBERT BENZINGER, OF CINCINNATI, OHIO. ASSIGNOR OF ONE-HALF TO WALTER M. SCHOENLE, OF CINCINNATI, OHIO.

CLOSURE.

1,336,811.

Specification of Letters Patent. Patented Apr. 13, 1920.

Application filed June 13, 1918. Serial No. 239,777.

To all whom it may concern:

Be it known that I, ALBERT BENZINGER, a citizen of the United States, and a resident of Cincinnati, in the county of Hamilton and 5 State of Ohio, have invented certain new and useful Improvements in Closures, of which the following is a specification.

My invention relates to closures for containers where ready opening is desirable, yet 10 requiring more or less tightness and security of closure.

The object of my invention is to simplify the construction of such closures without reducing, but rather increasing, their efficiency.

My invention consists in the combination of parts and in the details of construction and arrangement of parts as will herein-after be more fully described and claimed.

20 In the drawing:

Figure 1 is a vertical cross-section on a plane corresponding to the line 1—1 of Fig. 2, showing an example of my invention;

Fig. 2 is a horizontal cross-section on a 25 plane corresponding to the line 2—2 of Fig. 1 looking downward;

Fig. 3 is a plan view of the neck of the example of Figs. 1 and 2 with the plug or cap removed;

30 Fig. 4 is a sectional view similar to Fig. 1, but showing a modification;

Fig. 5 is another similar sectional view showing another modification;

Fig. 6 is another similar sectional view 35 showing a further modification of the example of Fig. 5;

Fig. 7 is a detail perspective view of the split washer of the example of Fig. 6;

Fig. 8 is a similar view of the elastic 40 washer of said example;

Fig. 9 is a vertical cross section of the upper part of a glass jar provided with a closure embodying my invention, the section being similar to that of Fig. 6; and

45 Fig. 10 is a diagram of the slot and boss.

My invention is well adapted as a closure for the radiators of automobiles, aircraft, motor boats and the like, and in Figs. 1 to 6, inclusive, I have illustrated it as being constructed for such a purpose. However, it is well adapted as a closure for any container such as a jar, jug, bottle, can or the like; being in fact adapted to take the place of any cap, stopper, lid, plug or other means of 55 closing any kind of container. This wide variety of uses is exemplified herein in Fig.

9 by showing how my invention is embodied in a jar, such as an ordinary fruit jar. From this it will be understood that the uses of the invention are not confined to the 60 examples shown, or to any of those specifically mentioned.

The device is especially desirable where it is desired to dispense with complicated and expensive screw threads as is the case with 65 both radiators and fruit jars, as well as many other containers which need not be mentioned.

In the examples of Figs. 1 to 6, inclusive, the radiator is not shown; but in each instance it will be understood that the neck 70 shown is of the kind adapted to be fixed to the radiator around its opening through which the cooling medium, such as water, is poured into the radiator.

75 In the example of Figs. 1 to 3, inclusive, the neck 1 is of the ordinary construction of rather heavy sheet metal which is drawn into a shape which is mainly cylindrical, with a radially outwardly extending annular flange 2 around its bottom. Ordinarily the plain cylindrical formation continues entirely to the upper end of the neck, and the interior of this upper end part is tapped or threaded to receive a suitably threaded 80 plug or cap which is screwed down therein; or the outside of this upper end part may be threaded and a cap with an internal thread 85 may be screwed down thereon.

In accordance with my invention, the 90 threads, either internally or externally, are dispensed with; the only additional detail of this neck construction being the provision of a plurality of relatively wide and deep grooves 3 which are pressed in the walls of 95 the neck 1 at suitable intervals therearound.

95 Each one of these grooves 3 comprises an upright part 4 leading down from the upper edge of the neck 1, and by a suitable curve 5 leading into a circumferential part 6 which terminates in a pocket 7 to which pocket this circumferential part 6 curves slightly upward. These grooves 3 are thus formed by pressing the sheet metal of the neck 1 outward.

100 The cap 8 comprises the depending flange 9 that fits rather snugly inside the neck 1 and integrally joins the hollow rim 10 around and integrally joining with the main upper part of the cap 8, which, as shown, is 110 preferably concavo-convex with its concave side downward. This cap 8 is made entirely

of a single piece of sheet metal. Its flange 9 has bosses 11 pressed outward in its sheet metal at the proper intervals therearound and a proper distance downward from the 5 lower side of the hollow rim 10 for these bosses to enter down through the upright parts 4 of the grooves 3 when the flange is inserted down into the neck 1, and to fit snugly up in the pockets 7 at the ends of the 10 grooves 3 with the lower side of the hollow rim 10 bearing tightly against the upper edge of the neck 1 when the cap has been twisted around in the neck after these bosses 15 have descended far enough to slide around in the circumferential parts 6 of the grooves 3.

This operation of the device is permitted, due to the resiliency of the sheet metal in the hollow rim 10. This hollow rim being 20 extended out over the upper edge of the neck 1, and its lower annular part 12 being virtually fulcrumed all around its extreme outer part where it joins the upright part of the rim, this part 12 is capable of yielding 25 slightly upwardly in its inner regions where it joins the flange 9. This yielding of this part of the cap is sufficient to permit the bosses 11 to pass along the parts 6 of the grooves 3 where the resistance of this part 30 12 of the cap is overcome by the user pressing down on it; and then when the bosses 11 have reached the pockets 7, the rim 10 will only partially regain its normal shape and will be holding these bosses 11 up in 35 these pockets 7. It will be understood that the entire upper part of the cap 8 also partakes somewhat of this movement or distortion which permits this completion of the closure and acts in thus maintaining it 40 against accidental derangement.

There is, therefore, a security of closure equal to that of a screw-threaded plug or cap; and the tightness of the closure will depend upon the evenness of bearing of the 45 lower side of the rim 10 on the upper edge of the neck 1. It will be understood that these parts may be made smooth and true enough to afford all of the tightness that is required of a radiator cap without the use 50 of any gasket, the same as with the threaded closure. At the same time, instead of the complicated threads, there are simply the grooves 3 pressed out in the sheet metal of the neck and the bosses 11 pressed out in the 55 sheet metal of the cap. Also, the cap of thin sheet metal is far more economically produced and conveniently used than the heavy cast caps or plugs generally employed where they must be threaded.

60 In the modification of Fig. 4, the neck 13 has its flange 14 as in the preceding example, but its upper part is enlarged so that it has an interior annular upwardly facing shoulder 15 at such a distance down from its 65 upper edge that when the cap 16 has its

flange 17 inserted into this enlarged upper part of the neck 13, the lower edge of the cap flange 17 will rest on the shoulder 15 while the lower side of the hollow rim 18 of the cap rests on the upper edge of the 70 neck 13.

Also in this example, the enlarged part of the neck 13 is provided with inwardly extending bosses 19 formed in its sheet metal as the bosses are formed in the sheet metal 75 of the cap flange in the preceding example; and the cap flange 17 has outwardly opening grooves 20 formed by pressing the material of the flange inward; each of these grooves 20 comprising the upright part 21 80 leading from the lower edge of the flange 17 upward, and leading, by a suitable curve 22, into the circumferential part 23 which terminates in the pocket 24. It will be seen that the principle of this construction is the 85 same as that of the preceding example; the grooves 20 of the cap receiving the bosses 19 of the neck when the flange 17 of the cap is inserted into the neck. In this case, the operation is permitted not only by the resiliency of the hollow rim 18, but by that 90 of the neck 13 in the vicinity of the shoulder 15. It will be understood that the depth of the pockets 24 is necessarily somewhat exaggerated in the drawing; as, in fact, is also that of the pockets 7 in Fig. 1. A very slight depth of these pockets, such as is consistent with the very slight yieldability of the sheet metal, is sufficient to very securely hold the cap in its closing position 95 when it has been twisted around in this way.

In the example of Fig. 5, the neck 25 has its lower flange 26; and it has its upper part reduced in diameter so as to leave an 100 annular upwardly facing shoulder 27 around its outside. Above this shoulder 27 the neck has the outwardly extending bosses 28. The cap 29 has the depending flange 30 and the hollow rim 31; and this flange 30 is adapted 110 to fit around the outside of the reduced upper part of the neck 25 with its lower edge down against the shoulder 27. The flange 30 has the inwardly opening grooves 32, each comprising the upright part 33 115 leading from the lower edge of the flange upward, and, by a curve 34, leading into the circumferential part 35 which terminates in the pocket 36. In this case, as in Fig. 4, the material of the neck, as well as 120 that of the cap, yields in the closing operation; the yielding being in the hollow rim 31 of the cap, and in the vicinity of the shoulder 27 of the neck. In this example, however, the upper edge of the neck 25 125 bears against the lower inner side of the main part of the cap 29 out adjacent to the hollow rim 31 outside the concavity of this part of the cap. It will be understood that here the resiliency of the entire upper part 130

of the cap is availed of in this automatic adjustment in the closing operation.

While the examples of Figs. 4 and 5 include the shoulders formed by enlarging or reducing the upper part of the neck, it will be understood that these shoulders may be omitted; in which case the bearing of the lower part of the hollow rim 18 on the upper edge of the neck 13 in Fig. 4, or the bearing of the lower inner side of the main part of the cap 29 on the upper edge of the neck 25 in Fig. 5, would determine the tightness of the closure. The example of Fig. 4 with the shoulder 15 omitted would be virtually the same as that of Fig. 1, except that the cap has the grooves and the neck has the bosses in Fig. 4, whereas in Fig. 1 the bosses are on the cap and the grooves are in the neck. Also, it will be understood that where the cap fits down over the neck as in Fig. 5, whether the shoulder 27 is provided or not, the bosses may be on the neck and the grooves in the cap, as shown, or the cap may have inwardly extending bosses entering outwardly facing grooves in the neck.

In the example of Fig. 6, the parts are substantially the same as in Fig. 5, but the neck is not so high above its shoulder 27, and an elastic washer or gasket 37 and a split resilient ring or washer 38 are interposed between the upper edge of the neck and the lower inner side of the cap; the split washer 38 being next to the cap and coacting with the hollow rim 31 and elastic washer 37 in making an adjustment of these parts, as well as of the lower edge of the cap to the shoulder 27, so as to effect a very tight closure such as may be depended upon to prevent the escape of either liquid or gaseous substances.

The glass jar 39 in Fig. 9 has the outwardly extending bosses 40 formed in the glass when the jar is made. These bosses are at suitable intervals around the neck of the jar and a proper distance down from the upper edge thereof, so that when the cap 29 is brought down over the neck of the jar the bosses 40 are received in the grooves 32 as in the preceding examples; and by twisting the cap around on the jar, the closure is completed. The elastic ring or gasket 41 is interposed between the upper edge of the jar and the lower side of the cap as is usual in jar closures. Here the simple bosses 40 take the place of the screw threads formed on the outside of the neck of an ordinary glass fruit jar or the like. It is extremely difficult to form sufficiently perfect threads in glass to insure that all of the threaded metal caps will fit all of the jars readily; and a great deal of difficulty is experienced in closing some jars because the glass threads fit the threads of the metal caps very imperfectly. Moreover, the jars are frequently broken in the efforts to close or

open them with such imperfect threads. Also, some of the threads are imperfect enough to impair the security of the closure.

With my invention depending upon the simple bosses to fit the simple grooves, and upon the resiliency of the cap itself with its hollow rim 31 in conjunction with that of the ring or gasket 41, the closing or opening of the jar is a very brief and easy operation. The lid or cap need be twisted through a distance of only about a half inch to either open or close the jar; instead of having to have several turns, as with the threaded closures. That is also an improvement over many other closures designed to dispense with screw threads in jar closures, because there are no extra pieces other than the elastic washer or gasket 41. Where no great security of closure is required, it will be seen that even the elastic washer may be dispensed with, as in the case of the radiator caps of the preceding examples.

While all of the examples show wide necks, it will be understood that bottles, jugs and the like with comparatively narrow necks may also be provided with my invention; since the resiliency and automatic adjustability of the closure is not dependent upon the width of the cap itself, but rather on the radial extent of the hollow rim; and this rim may be extended as far on a narrow-necked bottle or the like as upon a jar or other container with a wide neck.

If the cap is made of such relatively heavy material that its resiliency is negligible, some yieldable auxiliary means, such as the split washer of Figs. 6 and 7, may be employed either with or without the gasket shown in Fig. 8. In any case, whether the resiliency is provided in the cap itself or by an auxiliary means, the operation of the grooves and bosses will be substantially as hereinbefore described and as clearly indicated by the enlarged diagrammatic view in Fig. 10 where the groove outline is solid and the dotted circles indicate successive positions of the boss in the groove as one or the other of the parts is moved in the closing or opening operation, as has been described.

While certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

In a closure, two elements, one of which is adapted to fit in the other, said elements

being adapted to be relatively rotated when the one element fits in the other, a boss on one of said elements, the other one of said elements having a groove admitting said boss when the one element is inserted into the other, said groove extending circumferentially and terminating in a pocket, and admitting said boss to said pocket when said boss is relatively rotated with the one element inserted in the other as aforesaid, one of said elements being adapted to close the

other, and this one of said elements comprising a radially extended hollow annular rim of resilient material, thereby constituting yieldable means which permits said boss 15 to be received in said pocket during said relative rotation.

ALBERT BENZINGER.
